[57] **CLAIM**

The ornamental design for a body mounted pump for dispensing medication, as shown and described.

DESCRIPTION

FIG. 1 is a perspective view of one embodiment of a body mounted pump for dispensing medication showing our new design;

FIG. 2 is a top view of the embodiment of FIG. 1;
FIG. 3 is a side view of the embodiment of FIG. 1;
FIG. 4 is a bottom view of one side of the embodiment of FIG. 1;

FIG. 5 is an end view of the embodiment of FIG. 1;
FIG. 6 is an end view of the other end of the embodiment of FIG. 1;

FIG. 7 is a perspective view of another embodiment of this invention;

FIG. 8 is a top view of the embodiment of FIG. 7;

FIG. 9 is a side view of the embodiment of FIG. 7;

FIG. 10 is a bottom view of the embodiment of FIG. 7;

FIG. 11 is an end view of the embodiment of FIG. 7;
FIG. 12 is an end view of the other end of the embodiment of FIG. 7;

FIG. 13 is a perspective view of another embodiment of this invention;

FIG. 14 is a top view of the embodiment of FIG. 13;

FIG. 15 is a side view of the embodiment of FIG. 13;

FIG. 16 is a bottom view of the embodiment of FIG. 13;

FIG. 17 is an end view of the embodiment of FIG. 13;
FIG. 18 is an end view of the other end of the embodiment of FIG. 13.

The needle shown in broken lines has been disclosed for illustrative purposes only and forms no part of the claimed design.
